GRAIN BINDER.

No. 442,544.

Patented Dec. 9, 1890.

UNITED STATES PATENT OFFICE.

HENRY E. PRIDMORE, OF CHICAGO, ILLINOIS, ASSIGNOR TO THE MCCORMICK HARVESTING MACHINE COMPANY, OF SAME PLACE.

GRAIN-BINDER.

SPECIFICATION forming part of Letters Patent No. 442,544, dated December 9, 1890.

Application filed October 17, 1887. Serial No. 252,586. (No model.) Patented in England July 16, 1887, No. 9,992.

To all whom it may concern:

Be it known that I, HENRY E. PRIDMORE, a citizen of the United States, residing at Chicago, in the county of Cook and State of Illinois, have invented certain new and useful Improvements in Grain-Binders, (for which Letters Patent of the Kingdom of Great Britain, No. 9,992, dated July 16, 1887, have been issued to William P. Thompson as a communication from Cyrus H. McCormick, Jr.,) of which the following is a specification.

This invention relates in the main to that type of binders in which the tying-bill is stopped at the end of the knotting movement with its jaws trending outward in the direction of the extended cord-slot, so that the loop may be stripped therefrom and the ends wrenched from between the jaws by the direct strain of the sheaf as it is ejected by the discharge-arms of the binder, being assisted in the formation of the knot in a single complete revolution by the action of the holder, which is caused to carry the end strands around part way to meet the jaws before they complete their revolution, and thus enable them to accurately grasp the strands, and more particularly to improvements in the tying and holding head and the method of operating its parts.

In the drawings, Figure 1 is a rear elevation of so much of a grain-binder embodying said invention as is necessary to an understanding thereof; Fig. 2, an elevation from the stubble side with the breast-plate partly broken away; Fig. 3, an elevation from the front of the tyer-frame with knotter and holder mounted therein, showing also the bevel-pinions by which they are driven and a portion of the breast-plate; Fig. 4, an elevation from the inner or grain side with tyer-cam and breast-plate in vertical section; Fig. 5, a top plan view of the breast-plate, all other parts being removed; Fig. 6, an enlarged view of the knotter-head and tyer-cam partly in vertical section; Fig. 7, an enlarged detail of the breast-plate seen from the stubble side and in section to explain the shape of the cord stop or finger that obstructs the slot through said breast-plate; Fig. 8, an enlarged detail of the holder-disk and cord-knife seen from above, the holder-spindle being in transverse section; Figs. 9 and 10, enlarged details of the holder-shoe, the first representing it as attached to the stock or tyer-frame and pressed by its spring and the second as entirely detached; Fig. 11, an enlarged detail, in elevation, of the holder-disk and knife with the adjacent parts of the stock or tyer-frame, but omitting the holder-shoe; and Fig. 12, a section through said stock and its spindles and through the holder-shoe in its proper relative position, as indicated by the correspondingly-numbered lines in the preceding figure. Figs. 13, 14, and 15 are a diagrammatic series embracing the tying-bill and its spring-cam, the holder, and adjacent portions of the breast-plate, but with the tyer-frame and the operating-spindles in horizontal section, and all parts above removed to represent the successive stages of operation in forming the knot.

A represents the binder-arm shaft, and A' the vibrating needle or binder-arm actuated thereby. B is the decking or grain-chute through which said binder-arm plays, and C is the overhead breast-plate provided with pendent ribs c on either side of the longitudinal slot through which the binder-arm passes to reach the tying-bill and holder. This slot has heretofore been made of somewhat irregular outline, so as to afford an oblique finger D, setting from one side of said slot beneath the knotter in its revolution into a recess d at the other side and serving to deflect the cord and guide it more perfectly over the knotting-jaws. Such recess has been closed at its bottom by a web d', connecting it with the rib at that side, and thus underlying the point of the finger, so that the knotter in its revolution may be obliged to bend the cord into said recess as it carries it past the end of the finger, and so that the cord cannot accidentally escape until thus forcibly bent by the revolution of the knotting-jaws; but herein it is proposed to add to this finger near its base or the point from which it begins its projection from the side of the cord-slot and at the inner edge a boss or stud d'', curving downward toward the point or end of the finger, which itself at the end is curved slightly upward, so that the cord-strands may

first be deflected by said boss toward and perhaps past the center of the cord-slot, and so more perfectly brought over the chin of the tying-bill, and may then rest in the pocket thus formed by the inside edge of the finger until the tying-bill commences its revolution.

E is the tyer-frame, consisting of an upright post or bracket E', bolted at its foot to the breast-plate and supported above by 10 means of a sleeve E² upon the tyer-shaft, and except in some slight degree details not differing materially from the frame heretofore used. A bearing G, afforded by the tyer-frame or bracket, receives the tyer-spindle H radially to the tyer-shaft, or substantially so, and having at its head a bevel-pinion h, with a delay-shoe h', which respectively engage with a segment-rack i and delay-flange i' on the 15 face of the tyer-cam I, whereby the tyer-spindle is given one revolution and stopped with the tying-jaws pointing outward in the direction of the extended slot on the stubble side of the stop-finger in the breast-plate, which slot at this side of the finger is somewhat oblique, returning toward the base of said finger and outwardly at the same time, whereby said 20 jaws when at rest will be themselves somewhat oblique, so that the cord stretched between the holder and the finger may pass over their chin, as represented in Fig. 13.

The tying-bill itself does not or need not differ from those heretofore used, consisting, essentially, of a rigid jaw or crown k, integral with the spindle, and a second jaw k', pivoted thereto and having a heel-extension provided with an anti-friction roller k², engaged by a 25 spring-cam K, whereby this jaw is forcibly closed just before the tying-bill ceases its revolution and, is thereafter kept closed until a 30 fresh revolution is commenced and during the incipient stages of such revolution. A strong plate-spring L, resting at its upper end against a lug l from the tyer-frame, and between such lug and its lower end receiving an adjusting-screw l', whereby its stress may be increased or diminished, carries at said lower end the 35 cam whereby the movable jaw of the tying-bill is closed, and a lug l² from the tyer-frame, taking into a slot l³ in said cam, prevents it 40 from being carried laterally by the force exerted in the revolution of the knotter.

Outside of the tyer-spindle is the holder-spindle M, having a suitable bearing in the knotter frame or stock and set radially to the 45 tyer-shaft, thereby being oblique to the tyer-spindle, but at the same time in about the same vertical plane, parallel with the face of the tyer-cam. At its head the holder-spindle receives a bevel-pinion m and a delay-shoe 50 m', which respectively engage with a short segment-rack m² and delay-flange m³ on the face of the tyer-cam, the rack being in the present instance of sufficient length to give the spindle one-half of a complete revolution 55 and then cause it to be stopped by the delay-flange until the next knotting operation, but of course depending as to its length upon the

number of notches in the holder-disk. The holder-disk employed is of a shape that has come to be styled the "crown-disk"—that is, 70 it has an upturned annular flange n at or adjacent to its periphery, notched at suitable intervals for the reception of the cord, herein having four about equidistant notches, which agree with its semi-revolution for each binding operation. These notches are not cut completely to the bottom of the flange, but only part way, and while they may be cupped or rounded they are preferably undercut at their rear edge or that which acts against the 80 cord, so that the latter may not escape from them. At its exterior the flange has vertical corrugations n^x, and at one side adjacent to the tying-bill, or in such relation thereto as will be best understood by reference to the 85 last three figures or diagrammatic series, is pressed against by a shoe N, pivoted at n' to the tyer frame or stock and controlled as to its pressure by means of an adjusting-screw n², passing through it and entering said stock, 90 and by a coiled spring n³, interposed between its shank and the head of said shoe. The holder-disk carries two knives o o', diametrically opposite each other, projecting upward from a plate O of hardened metal secured 95 to the bottom of the holder-disk by slots and set-screws o², so as to be adjustable. These knives are so arranged that each of them runs a little behind an adjacent notch in the disk, and they are set so far out from the upturned 100 flange of this disk that they pass outside of the holder-shoe in the revolution of the knitter.

Now in operation, the parts being in proper relative position, (indicated in Fig. 13,) with 105 the holding-strand clamped between the exterior of the crown-disk and the opposing face of the shoe, thence belayed through the first notch in crown-disk just beyond said shoe and back past the tooth immediately to the 110 rear, thence through the second notch and slightly clamped again by the holder-shoe, as shown, then obliquely over the chin of the tying-bill, past its chin, down across the stop-finger, through the cord-slot in the breast-plate, and through the eye of the needle, the 115 latter rises, bringing the new strand up, laying it over the stop-finger and slightly over the chin of the tying-bill, but in direct line with the cord-slot, and thus not parallel with the 120 first strand, which has been carried away from that line toward the tyer-spindle in the previous operation to reach the position just explained. The new strand now is held by the needle almost directly over, but slightly 125 in advance of, the third and fourth notches in the holder, and the tying-bill starts, catching the cords and carrying them in the first half of its turn over the end of the stop-finger, as shown in Fig. 14, thus looping them. 130 Almost immediately following the incipient movement of the tying-bill the holder-disk also starts, and the strand from the needle drops into the third notch, and also it may

be into the fourth notch, while the old strand is released from the primary grasp of the shoe in rear of the first notch, still remaining grasped between the shoe and the flange in 5 rear of the second notch, with a constantly increasing grip, yet weaker than the first grip when it was held at two points. Thus during the first part of the revolution of the knotter when slack is demanded this strand, 10 being released at the primary point of holding, is allowed to slip through the holder as drawn upon by the knotter; but during the latter part of the revolution of said knotter when no slack is demanded the grip increases, 15 so as to hold the strand practically rigid. Meanwhile the revolution of the tying-bill gradually belays the strand between the eye of the needle and the holder around the tooth between the third and fourth notches of the 20 holder-disk, therefore increasing the tension and preventing this strand, which at first pulled freely from the needle, restrained only by the primary tension on the cord, from running out with merely the same resistance 25 when the coming around of the tying-bill in the last half of its revolution makes slack no longer necessary; or, in other words, the tension of the strand from the needle is increased by the action of the crown-disk as a secondary 30 tension concurrently with the increasing grip upon the old strand as the knotter passes the first half of its revolution. Finally, when the tying-bill approaches the end of its revolution the needle-strand has been carried 35 past the shoe, as shown in the fifteenth figure, bringing it alongside the old strand and bending it over the edge of said shoe, and also bringing it up against the spindle—that is, it has been moved from the position in which it 40 originally laid to the position occupied by the old strand between the holder and the tying-bill, and, together with the old strand, has entered or enters just before the termination of the revolution of the tying-bill between the 45 jaws of the latter, which thereupon close, when the continued revolution of the holder-disk carries the knife on that side against the two strands, severing them, and the sheaf is ready to be ejected. Finally, the holder-disk reaches the position shown in the thirteenth figure, comes to a stop, having made a 50 half of a revolution, brought the second knife into the position originally occupied by the first, and grasped the new strand, now itself 55 becoming the old strand, with a primary and a secondary grip ready for the next action.

I claim—

1. The combination, substantially as hereinbefore set forth, with the tying - bill and a suitable holder, of an oblique rigid stop-finger setting out from one side of the cord-slot toward the other, and along and over the end of which the tying-bill carries the cord strands as it turns, and an upstanding boss or deflector located at the base and inside edge of 60 said stop-finger.

2. The combination, substantially as hereinbefore set forth, with the tying - bill and mechanism for giving it a single rotation and stopping it with its jaws trending outwardly 70 in the direction of the extended cord-slot, of a holder arranged to carry the cord - strands around to meet the tying-bill in its revolution, a stop-finger in the cord-slot, along and over the end of which the tying-bill carries said 75 strands as it turns, and an upstanding boss or deflector located at the inside edge of said stop-finger.

3. The combination, substantially as hereinbefore set forth, with the tying - bill and 80 binder-arm, of a tension device arranged and timed, practically as described, to act upon the spool - strand independently of the old strand between the eye of the binder-arm and the tying-jaws toward the close of the revolution 85 of the latter and before said strand enters beneath the holder-shoe.

4. The combination, substantially as hereinbefore set forth, with the tying - bill and binder-arm, of a crown disk-holder arranged 90 to receive the strand from the binder-arm in two of its notches, whereby said strand is belayed over the finger between said notches in the revolution of the holder-disk to apply tension thereon between the point of the binder-arm and the tying-bill after the latter ceases to demand slack.

5. The combination, substantially as hereinbefore set forth, with the tying - bill, of a crown disk-holder having four notches, a shoe 100 pressing upon the exterior of said holder adjacent to the tying-bill, and a binder-arm arranged to lay its strand in two of said notches in advance of the shoe, whereby they are belayed upon the tooth between concurrently 105 with the increase of grasp upon the old strand as the tying-bill ceases to demand slack.

6. The combination, substantially as hereinbefore set forth, of the tying - bill, its spindle, the pinion and delay-shoe upon said spindle, the segment-rack and delay-flange upon the tyer-cam, arranged to impart a single revolution to the tying - bill and stop it with its jaws trending outwardly, the crown holder-disk and its spindle, the pinion and delay-shoe 110 upon said spindle, the segment-rack and delay-flange upon the tyer-cam arranged to rotate said disk, the shoe pressing upon the exterior of said disk, and a knife or knives carried by said disk and passing outside of the 115 shoe.

7. The combination, substantially as hereinbefore set forth, of the tying - bill, its spindle, pinion, and delay-shoe, the segment-rack and delay-flange upon the tyer-cam, adapted 125 to impart a single revolution to the tying-bill and stop it with its jaws trending outwardly, the four-notched crown disk-holder and its spindle, the pinion and delay-shoe upon said spindle, the segment-rack and delay-flange 130 upon the tyer-cam proportioned to impart a half-revolution to the holder - disk, the shoe

pressing upon the exterior of the holder-disk, and the two knives carried by said disk and arranged to pass outside of the shoe.

8. The crown holder-disk having four notches, combined with a shoe pressing upon the exterior of its flange, and mechanism which gives it a half-rotation for each binding operation, whereby a primary and secondary grasp are taken upon the strand and the

primary grasp released, so that said strand 10 may pull through as slack is demanded in the first part of the revolution of the tying-bill and the grasp increased in the latter half.
